[57] CLAIM

The ornamental design for an iron-type head for a golf club, as shown and described.

DESCRIPTION

FIG. 1 is a perspective view showing the rear and right sides of an iron-type head for a golf club embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a sectional view taken on the line 8—8 of FIG. 3;

FIG. 9 is an enlarged sectional view taken on the line 9—9 of FIG. 3;

FIG. 10 is a perspective view showing the rear and right sides of an alternative form of my new design, the front, right and left side elevational views and the top and bottom plan views being identical to the embodiment of FIGS. 1-7; FIG. 11 is a rear elevational view of the embodiment of FIG. 10;

FIG. 12 is a sectional view taken on the line 12—12 of FIG. 11; and,

FIG. 13 is an enlarged sectional view taken on the line 13—13 of FIG. 11.
